CLAIM

The ornamental design for a light fixture, as shown and described.

DESCRIPTION

FIG. 1 is a bottom perspective view of a light fixture in accordance with my design, illustrating multiple adjustable positions of various portions of the light fixture;

FIG. 2 is a front elevation view of the light fixture in accordance with my design, illustrating multiple adjustable positions of various portions of the light fixture;

FIG. 3 is a back elevation view of the light fixture in accordance with my design, illustrating multiple adjustable positions of various portions of the light fixture;

FIG. 4 is a top plan view of the light fixture in accordance with my design, illustrating multiple adjustable positions of various portions of the light fixture;

FIG. 5 is a bottom plan view of the light fixture in accordance with my design, illustrating multiple adjustable positions of various portions of the light fixture;

FIG. 6 is a side elevation view of the light fixture in accordance with my design illustrating multiple adjustable positions of various portions of the light fixture;

FIG. 7 is an opposite side elevation view of the light fixture in accordance with my design, illustrating adjustable positions; and,

FIG. 8 is a bottom perspective view of the light fixture in accordance with my design, illustrating multiple adjustable positions of various portions of the light fixture.

The broken lines showing environmental structure are for illustrative purposes only and form no part of the claimed design.

The light fixture of FIGS. 1 and 4-8 is shown broken away to indicate that no specific length is claimed.
